STRIP FEEDING MECHANISM FOR AUTOGRAPHIC REGISTER

Walter E. Oliver, Quincy, Mass.

Application April 27, 1953, Serial No. 351,340

8 Claims. (Cl. 271—2.4)

This invention relates to autographic registers by which is meant a machine of the well-known type in which paper strips stored in the register are advanced through successive, measured distances into and past a writing position over a platen. In this writing position the strips ordinarily cooperate with intercollated carbon paper permitting a number of copies to be made simultaneously. The sections of strip thus successively brought to writing position are usually printed blank forms, or "tickets" as they are commonly called, and after one has been filled out the machine is operated to bring a second into writing position while at least one or more of the inscribed tickets is fed to a position exterior to the casing of the machine where they may be torn off or cut off. In particular these successive feeding movements may be effected by movements of an external handle and it is desirable that this handle have an oscillatory or reciprocating stroke which in one phase thereof effects the movement of the strips. The movement should be an accurate one so that the various tickets will be separated at the proper lines of division. The present invention relates more particularly to a mechanism for transmitting the feeding movement from such an oscillatory handle to the paper strips by a rugged, simple and fool-proof mechanism.

In the form of the invention shown the actual feed of the strips is effected in known manner by means of pinwheels having teeth which enter a series of openings along the margins of the strips.

My invention will be well understood by reference to the following description of the illustrative embodiment thereof shown by way of example in the accompanying drawings, wherein:

Fig. 1 is a plan view of an autographic register incorporating a feeding mechanism illustrative of the invention, parts being broken away;

Fig. 2 is a section on line 2—2 of Fig. 1, the stationery strips being omitted;

Fig. 3 is a section on line 3—3 of Fig. 1, but on a larger scale, showing the parts in the normal position of rest;

Fig. 4 shows parts in position for initiating a new feeding movement;

Fig. 5 shows the same parts after the incremental feeding movement is completed;

Fig. 6 shows the parts just after the actuating handle has returned to initial position; and

Fig. 7 shows a fragmentary section on line 7—7 of Fig. 3 on a still larger scale.

Referring now to the drawings, I there show a register of the pinwheel feed type in which the incremental feed of the strips is effected by oscillatory movements of a handle acting through a train of mechanism to the pinwheels the construction of the train being illustrative of the invention.

Referring more particularly to Figs. 1 and 2 of the drawings, the register embodies a suitable casing 10 in which the paper strips are stored and having an upper surface or platen 12 over the rear end of which, viewing

2

Fig. 1, the strips of papers are drawn and over which they are advanced, and beyond which they are fed after inscription beneath an overhanging member 14, the leading edge of which forms a ledger blade for tearing off the inscribed tickets, leaving the following, uninscribed set in position over the platen. For feeding the strips *s* the pinwheels 16 project up through the platen at either side thereof, to engage the holes *h* in the margins of the paper strips as seen in Fig. 1. The strips are omitted in Fig. 2. Carbon sheets, not shown but stored in a compartment 18 lateral to the platen, may be drawn transversely across the latter and intercollated with the strips in well-known manner. In the construction shown one turn of the pinwheels 16 serves to advance the strips one ticket's length. The pinwheels 16 may be mounted on a common shaft 20 carrying a pinion 22 meshing with a driving gear 24, which in the example shown is four times the diameter of the pinion, and the driving gear may be advanced in one direction by the means to be described by angular movement of an external, crank-like handle 26, through a stroke of approximately 90°, resulting in a complete rotation of pinion 22 and the pinwheels, and the feeding of one ticket length. Herein I have shown a spring pawl 28 which clatters over the teeth of gear 24 as the tickets are advanced but engages the teeth to prevent retrograde movement of the tickets.

In practice the user stands or sits with the register before him in the position of Fig. 1 and writes on the strips exposed over the platen with his right hand. The handle 26 is at the left, and herein the feeding movement of the strips is effected by pulling back on the handle toward the user, moving it from the position shown in Fig. 3, through a stroke of approximately 90° to the position illustrated in Fig. 5.

What has been so far described is not in itself essentially new and the language might apply with perhaps minor changes to mechanisms of the prior art, the present invention being concerned more particularly with the particular arrangement for transmitting the feeding stroke of the handle crank to the pinwheel shaft, the stopping and locking of the mechanism at the proper times, and the arrangement providing for the automatic return of the handle and the release of the locking mechanism for a second feeding stroke when desired.

Herein, as best shown in Fig. 7, the gear 24 carries, as a part of a single integral element, an indexing disc 30 and a ratchet wheel 32. As seen in Fig. 3, the indexing disc 30 has at suitable intervals thereabout square-sided recesses 34 which are adapted to be entered by the square-sided nose of a pivoted detent 36, positively to lock the disc and the associated parts against movement in either direction. The detent is pivoted on a fixed center 38 and is provided with a tail 40 acted on by a spring 42 which biases it toward the locking position. The recesses 34 are so spaced from one another that a movement which carries successive recesses opposite the detent corresponds to a movement of the stationery strips for one ticket length. The teeth of ratchet wheel 32 are similarly spaced. Thus, in the example shown one turn of pinwheel 16 advances the strips one ticket length. The value of the gear train is one-quarter and there are four recesses 34. If the head of the ticket is directly under the edge of the ledger blade 14 when a feeding movement is commenced the head of the succeeding ticket will be there when the wheel and disc have advanced for a distance between successive teeth of the former and successive recesses of the latter.

The parts are moved by a driver or pawl carrier 44, which is loose on the shaft 46 on which the gear, disc and ratchet wheel are mounted, and the handle 26 is rigid with this pawl carrier. The pawl carrier supports a driving pawl 48 (the end of which appears substantially at

the seven o'clock position in Fig. 3) which is spring-pressed toward the ratchet wheel. The pawl carrier also has an arm provided with a bent-over end 50, see Fig. 7, the path of which is such that, when the pawl carrier is rotated, it engages the tail 40 of the detent 36 to rock the detent against its spring 42 and so retract it. Also, at about the one o'clock position in Fig. 3, there is a catch 52 which will be more fully described hereinafter.

The pawl carrier is acted on by a like extension spring 54 which tends to return it with a counterclockwise rotation to the position of Fig. 3 when it has been displaced to the position of Fig. 5. The points of connection of the spring 54 are such that in Fig. 3 the spring acts approximately radially of the shaft 46 and exerts only a slight turning moment on the shaft, particularly as it is in that position substantially relaxed. Thus any stored up energy remaining in it is not effective to overcome the spring 42 and release the detent 36. In this normal rest position of the parts seen in Fig. 3 the driving pawl 48 is just in advance of one of the teeth of the ratchet wheel 32.

To operate the mechanism and cause feeding of the strips the handle 26 is grasped and rocked counterclockwise for a short distance. The extent of this motion is preferably limited by means hereinafter described. This action overcomes the spring 42 and the arm 50, acting on the tail 40 of the detent, frees the parts; the driving pawl 48 is moved back and is pressed by its spring into engagement with a tooth of the ratchet wheel 32 as seen in Fig. 4. The feed stroke is then effected by a clockwise movement of the handle, driving the parts through the pawl 48 to the position of Fig. 5. When the detent 36 is released by the part 50 in the beginning of this motion, its nose falls on the edge of the indexing disc 30 between the recesses 34 therein, and slides thereover until the stroke is completed. To insure its entry in the following recess the stroke is limited and herein the end of pawl 48 strikes a fixed stop, herein a screw 56, mounted in a bracket 58 and adjustably secured by a lock nut 60 which is so positioned as to press the pawl inwardly toward the ratchet wheel and thus serve as a positive stop against further movement of the parts. In this position a recess 34 is opposite the nose of the detent pawl 36 which enters smoothly therein.

It would be possible to ease the handle 26 back from the position of Fig. 5 to the position of Fig. 3 wherein the cross arm 50 is just in contact with the tail 40 of the detent. It is however desirable to be able to let go the handle and have it automatically returned by spring 54. The momentum of the parts on such a rapid return would be likely to cause release of the detent 36 and therefore means are provided to check the counterclockwise movement of the pawl carrier 44 and to bring it to rest in the position of Fig. 3, this means going out of action after the parts have so been brought to rest. This function is performed by the catch 52 which has previously been referred to in a general way.

The catch 52 is pivoted between its ends on an arm of the carrier and can rest in two positions wherein it is supported against gravity at either side of its pivot by a flange 62 on that arm, one position being shown in Fig. 5 where the catch is below the horizontal, and another in Fig. 3 where it is above. The center of gravity moves from about a five o'clock position in Fig. 5 to about a one o'clock position in Fig. 3. As will be apparent, the center of gravity is so related to the pivot that there is only a very slight turning moment tending to turn the catch to the position of Fig. 3 until after the parts are well past the three o'clock position. Now if the pawl carrier 44 was moving rapidly under the influence of the spring 54, the action of centrifugal force on the catch tends to swing it outwardly from the center and maintain it in the same position as in Fig. 5 as seen in Fig. 6. The end of the catch has two shoulders, an inner shoulder 64 extending furthest in a counterclockwise direction from its pivot, and

an outer shoulder 46 spaced rearwardly from the shoulder 64, if we consider counterclockwise rotation to be a forward movement. When moving rapidly from the position of Fig. 5, and therefore under an influence of substantial centrifugal force as it passes the horizontal, the catch will remain in that position as it reaches the position of Fig. 6, and the shoulder 64 will strike a fixed stop 68 and bring the carrier to rest in the position there shown. The arm 50 has then reached the tail 40 of the detent but does not strike it with sufficient force to release the latter, and the driving pawl 48 comes to rest just in advance of the next tooth on the ratchet wheel. It will be noted however that the parts are not jammed in the position of Fig. 6. A slight bounce of the parts permits the catch to drop inwardly under gravity to the position of Fig. 3.

When the handle 26 is grasped to start a new cycle, an initial counterclockwise movement of the handle against the force of spring 42 brings the shoulder 64 against the stop 68 and limits this movement which, however, is sufficient to retract the detent and permit the driving pawl 48 to drop into its wheel as seen in Fig. 4. The handle is, as it were, cocked and the pawl is ready to pick up the ratchet wheel and drive the mechanism when the handle is moved clockwise.

While the force required to cock the handle is not great the resistance is sufficient to prevent casual and unintentional displacement of the parts. If the handle is idly moved clockwise while the parts are in the position of Fig. 3, the pawl 48 moves over the ratchet wheel idly in the space between successive teeth. This wheel and the other parts remain locked by detent 36. Casual jiggling on the handle will be ineffective to move the paper forward.

A definite length of strip is fed on each cycle. The parts are stopped dead and locked dead in that position without possibility of overthrow or rebound. When a feeding movement is started it must be completed. The user cannot pump on the handle and feed the strips in that manner. If the pawl is moved part way no feeding is effected, and if the handle is returned either the resistance of the spring 42 or the shoulder 64 of the catch 52 will act to stop this reverse movement before the pawl 48 can pick up another tooth.

I am aware that the invention may be embodied in other specific forms without departing from the spirit or essential attributes thereof, and I therefore desire the present embodiment to be considered in all respects as illustrative and not restrictive, as is in fact clear in several matters from the description itself. Reference is to be had to the appended claims to indicate those principles of the invention exemplified by the particular embodiment described and which I desire to secure by Letters Patent.

I claim:

1. In a register of the type in which stationery strips are advanced by successive steps of predetermined length into and past a writing position by successive oscillatory movements of an external handle having a driving connection with the feeding means, a driver moving with the handle and a train of mechanism driven therefrom, the last element of which train directly acts on the strips, and including a ratchet wheel and an indexing disc which move as one, the indexing disc having recesses spaced to correspond to advance of the strips through one such step and the ratchet wheel having similarly spaced teeth, a movably mounted positive locking detent for entering said recesses having a tail, a spring for biasing the detent toward locking position, said driver carrying a pawl for cooperation with said ratchet wheel, an arm moving with the driver to engage the tail of the detent on return movement of the driver to a position wherein the pawl will engage a tooth of the ratchet wheel for a second stroke and, consequently to such engagement, to move the detent against its spring, a spring operatively related to the driver to be stressed consequently to the movement thereof to its forward position and resiliently returning

the driver from that position, which spring is substantially completely relaxed when the said arm engages the tail so that its remaining stored energy is in itself insufficient to overcome the spring of the detent to release the latter.

2. In a register of the type in which stationary strips are advanced by successive steps of predetermined length into and past a writing position by successive oscillatory movements of an external handle having a driving connection with the feeding means, a driver moving with the handle and a train of mechanism driven therefrom, the last element of which train directly acts on the strips, and including a ratchet wheel and an indexing disc which move as one, the indexing disc having recesses spaced to correspond to advance of the strips through one such step and the ratchet wheel having similarly spaced teeth, a movably mounted positive locking detent for entering said recesses having a tail, a spring for biasing the detent toward locking position, said driver carrying a pawl for cooperation with said ratchet wheel, means for limiting the forward stroke of the driver comprising a fixed stop engaged by the pawl and acting to press the same toward the wheel, an arm moving with the driver to engage the tail of the detent on return movement of the driver to a position wherein the pawl will engage a tooth of the ratchet wheel for a second stroke and, consequently to such engagement, to move the detent against its spring, a spring operatively related to the driver to be stressed consequently to the movement thereof to its forward position and resiliently returning the driver from that position, which spring is substantially completely relaxed when the said arm engages the tail so that its remaining stored energy is in itself insufficient to overcome the spring of the detent to release the latter.

3. In a register of the type in which stationary strips are advanced by successive steps of predetermined length into and past a writing position by successive oscillatory movements of an external handle having a driving connection with the feeding means, a driver moving with the handle and a train of mechanism driven therefrom, the last element of which train directly acts on the strips, and including a ratchet wheel and an indexing disc which move as one, the indexing disc having recesses spaced to correspond to advance of the strips through one such step and the ratchet wheel having similarly spaced teeth, a movably mounted positive locking detent for entering said recesses and biased toward locking position, said driver carrying a pawl for cooperating with the ratchet wheel, means for limiting the extremes of the oscillating stroke of the handle and driver, the index disc presenting at the limits one of its recesses to the detent, means moving with the driver for retracting the detent when the driver comes to the extreme of its rearward stroke, means for returning the handle when it is released on completion of its forward stroke and means responsive to such release for temporarily bringing it to rest before it reaches that extreme position and retracts the detent.

4. In a register of the type in which stationary strips are advanced by successive steps of predetermined length into and past a writing position by successive oscillatory movements of an external handle having a driving connection with the feeding means, a driver moving with the handle and a train of mechanism driven therefrom, the last element of which train directly acts on the strips, and including a ratchet wheel and an indexing disc which move as one, the indexing disc having recesses spaced to correspond to advance of the strips through one such step and the ratchet wheel having similarly spaced teeth, a movably mounted positive locking detent for entering said recesses and biased toward locking position, said driver carrying a pawl for cooperating with the ratchet wheel, means for delimiting the oscillating stroke of the handle and driver, the index disc presenting at the limits one of its recesses to the detent, means moving with the driver for retracting the detent when the driver comes to the extreme of its rearward stroke, and means

for bringing the parts temporarily to rest before the driver reaches that extreme position, which means goes out of action when the parts have been so brought to rest.

5. In a register of the type in which stationary strips are advanced by successive steps of predetermined length into and past a writing position by successive oscillatory movements of an external handle having a driving connection with the feeding means, a driver moving with the handle and a train of mechanism driven therefrom, the last element of which train directly acts on the strips, and including a ratchet wheel and an indexing disc which move as one, the indexing disc having recesses spaced to correspond to advance of the strips through one such step and the ratchet wheel having similarly spaced teeth, a positive locking detent for entering said recesses and biased toward locking position, said driver carrying a pawl for cooperating with the ratchet wheel, means for returning the handle when it is released on completion of the forward stroke, means to retract the detent actuated by the movement of the driver to a position for engaging the pawl for a second stroke, and means responsive to centrifugal force of the driver for checking such return movement before such position is reached.

20 6. In a register of the type in which stationary strips are advanced by successive steps of predetermined length into and past a writing position by successive oscillatory movements of an external handle having a driving connection with the feeding means, a driver moving with the handle and a train of mechanism driven therefrom, the last element of which train directly acts on the strips, and including a ratchet wheel and an indexing disc which move as one, the indexing disc having recesses spaced to correspond to advance of the strips through one such step and the ratchet wheel having similarly spaced teeth, a positive locking detent for entering said recesses and biased toward locking position, said driver carrying a pawl for cooperating with the ratchet wheel, means for returning the handle when it is released on the forward stroke, means to retract the detent actuated by movement of the driver to a position for engaging the pawl for a second stroke, and a pivoted catch on the driver responsive to gravity and centrifugal force and having a shoulder, a fixed stop in the path of said shoulder when it is swung outwardly to check such return movement before such position is reached.

40 7. In a register of the type in which stationary strips are advanced by successive steps of predetermined length into and past a writing position by successive oscillatory movements of an external handle having a driving connection with the feeding means, a driver moving with the handle and a train of mechanism driven therefrom, the last element of which train directly acts on the strips, and including a ratchet wheel and an indexing disc which move as one, the indexing disc having recesses spaced to correspond to advance of the strips through one such step and the ratchet wheel having similarly spaced teeth, a positive locking detent for entering said recesses and biased toward locking position, said driver carrying a pawl for cooperating with the ratchet wheel, means for returning the handle when it is released on the forward stroke, means to retract the detent actuated by movement of the driver to a position for engaging the pawl for a second stroke, and a pivoted catch on the driver responsive to gravity and centrifugal force having a shoulder, a fixed stop in the path of said shoulder when it is swung outwardly to check such return movement before such position is reached, the catch having a second shoulder, which when the catch is positioned inwardly, cooperates with the stop to limit return movement of the driver substantially in such position of engagement.

65 8. In a register of the type in which stationary strips are advanced by successive steps of predetermined length into and past a writing position by successive oscillatory movements of an external handle having a driving con-

nection with the feeding means, a driver moving with the handle and a train of mechanism driven therefrom, the last element of which train directly acts on the strips, and including a ratchet wheel and an indexing disc which move as one, the indexing disc having recesses spaced to correspond to advance of the strips through one such step and the ratchet wheel having similarly spaced teeth, a positive locking detent for entering said recesses and biased toward locking position, said driver carrying a pawl for cooperating with the ratchet wheel, means for rapidly returning the driver on release of the handle after completion of the feeding stroke, means moving with the driver to retract the detent when the pawl engages a tooth of the ratchet wheel for a second stroke, and means

for checking the driver before it reaches the position wherein the detent is retracted, which means goes out of action when the parts have come to rest to permit intentional further retraction of the handle to engage the pawl and release the detent.
